UNITED STATES PATENT OFFICE

CHARLES H. COLLINS, DECEASED, LATE OF AMSTERDAM, NEW YORK, BY MARY COLLINS OF CRANESVILLE, NEW YORK, EXECUTRIX

MACHINE FOR WINDING TUBE-FRAME SPOOLS

Refile for abandoned application Serial No. 83,787, filed January 26, 1926. This application filed December 22, 1927. Serial No. 241,975.

This invention relates to devices for winding a multiple number of yarns upon a single spool, particularly tuft yarn spools used on the tube frame of Axminster looms.

5 The object of this invention is to provide a winding mechanism which will so compact the yarns as they are laid upon the spools that an appreciably greater length of yarn may be placed thereon without increase in 10 the maximum diameter of the filled spool; thereby making possible a considerable increase in the product from a loom, equipped with tuft yarn spools which have been wound by this improved device before it will become 15 necessary to replace or rewind the spools.

The object of this invention is accomplished by means of an improved spool winding mechanism which is very similar to that disclosed by the United States Patent No. 20 1,185,633, granted June 6, 1916, but differs therefrom in certain vital particulars which will be hereinafter described and claimed. This further improved spool winding device is illustrated in the accompanying drawings, 25 in which:

Fig. 1 is a side elevation, parts omitted, of this further improved spool winding device with a partly filled "overwound" spool therein.

30 Fig. 2 is a front elevation of the winding rolls and their actuating mechanism, with a partly filled spool in place therebetween, parts broken away.

Fig. 3 is a cross section through the winding rolls, as along the line $x-x$ in Fig. 2, and 35 illustrates the manner in which an "underwound" spool is filled by the same device.

The same reference characters refer to the same parts throughout the several views.

40 Referring to the drawings: F represents the frame of the device, or a portion thereof, in which there is journalled a spaced pair of rolls R^1 and R^2 , which are of the same diameter and are driven at the same speed by any 45 suitable means, here shown as the spur gears r, r , attached to the shafts thereof, and both of which mesh with a driving spur gear dg , secured on the shaft 35, and which is driven as by a chain 37, and sprocket 36, from any 50 suitable and available source of power (not

shown) so controlled that the direction of rotation may be reversed at will.

To the shaft 35 there is joined, by means of a suitable flexible coupling or universal joint 34, an extension 33, which in turn is 55 connected to a second universal joint 32, secured to or forming a part of the gear sleeve 31, pivoted, and limitedly shiftable longitudinally on a stud 30. The connection between the extension 33, and one of the universal joints 34 or 32, is such that a limited telescoping between the extension and the coupling is possible. See telescopic joint with pin and slot connection 33*, Figure 2.

The gears 28, and 29, on the sleeve 31, are of 65 different diameters, and the gears 24 and 25, on the sleeve 26 are also of different diameters, the relative diameters thereof being such that when the gears 24 and 28 are in mesh the peripheral speed of the 70 roll S, driven by the sprocket 23 on the sleeve 26, through the chain 22, and sprocket 21, will be slightly greater than that of the rolls R^1 and R^2 , while the peripheral speed of the roll S when the gears 25 and 29 are in 75 mesh will be slightly less than that of the rolls R^1 and R^2 .

The downwardly projecting ends of the member u , are hinged at h^1 and h^2 , to parts h^3 and h^4 respectively which are slidable vertically in the end portions of the frame F, and the studs which carry the sleeves 26 and 31 are mounted in or are secured on the same vertically slidable piece so that as the spool fills 80 they and the roll S will move upward as a 85 unit.

Suitable means, as for instance, the lever 15 pivoted at 16, and the handle 17, are provided whereby the sleeve 31, may be shifted at will 90 so as to change the speed of the roll S. While I now prefer to provide for the change in the direction of rotation of the rolls at the source of power, or between such source and the winding machine, I may include a change 95 mechanism in the machine itself.

In a device illustrated by the prior patent, above identified, tension is applied to the 100 yarns as they are wound upon the spools, by reason of their being drawn between measur-

ing rolls which are driven thereby and so cause tension thereon.

In this improved apparatus a substantially like result is attained without this external tensioning means. In this present device, the desired tension on the yarns is secured by having the peripheral speed of the roll S, such that it will act as a brake to retard the free passage of the yarns thereby as the spool is rotated, by causing a slip to occur between the yarns and that roll.

In order to properly wind both "overwound" and "underwound" spools in the same device, there has been provided means whereby the speed of the roll S may be changed at will, for when an "overwound" spool is to be filled it is necessary that it have a slightly lesser peripheral speed, and when an "underwound" spool a slightly greater peripheral speed than that of the rolls R¹ and R², in order that the proper amount of slip to produce the desired tension, may occur and that in the right direction.

It is, of course, obvious that if but one type of wound spool is desired the means for changing the speed of the roll S, may be omitted, and without departing from the spirit of this invention.

This application is a refile for abandoned application Serial No. 83,787, filed Jan. 26, 1926.

What is claimed is:

1. In a device for winding yarns onto a tube frame spool: a spaced fixedly supported pair of rolls adapted to support a spool placed thereon and to contact with the yarns being wound thereon; means for causing rotation of said rolls at the same peripheral speed; a yieldingly supported roll adapted to lie in contact with the yarns being wound on said spool on said pair of rolls; means whereby either one of two peripheral speeds, one greater than, the other less than the peripheral speed of said pair of rolls, will be imparted to said yieldingly supported roll when said pair of rolls are caused to rotate.

2. A process for winding yarns onto a tube frame spool, and consisting in supporting and driving the spool between a multiple number of driven rolls which contact with the surface of the layer of yarns as they are laid upon the spool, one of said rolls adapted to yield as the spool fills, and one of them having a peripheral speed different from that of the others whereby braking tension is applied to the yarns as they pass thereunder.

In testimony whereof I have affixed my signature.

MARY COLLINS,

60 Executrix U:W of Charles H. Collins, Deceased.
